UNITED STATES PATENT OFFICE.

WILLIAM D. BALDWIN, OF NEW YORK, N. Y., ASSIGNOR TO OTIS ELEVATOR COMPANY,
OF JERSEY CITY, NEW JERSEY, A CORPORATION OF NEW JERSEY.

MULTIPLE-CAR ELEVATOR SYSTEM.

1,218,617.

Specification of Letters Patent. Patented Mar. 13, 1917

Application filed January 17, 1913. Serial No. 742,530.

To all whom it may concern:

Be it known that I, WILLIAM D. BALDWIN, a citizen of the United States, residing in New York, in the county of New York and State of New York, have invented a new and useful Improvement in Multiple-Car Elevator Systems, of which the following is a specification.

This invention relates to multiple car elevator systems, and more particularly has reference to an elevator system for use in high buildings, whereby a plurality of elevator cars can be operated in the same shaft; and an object of the invention is to provide an elevator system wherein two or more cars are independently operated in the same shaft, thereby economizing in space and in other ways, automatic controlling means being provided for preventing collisions either by one car overtaking another or by the cars running oppositely toward each other.

A further object of the invention is the provision of a common hatchway in which are arranged a plurality of independently controlled elevator cars, the hatchway being provided with branch hatchways which, together with the common hatchway, terminate at the same floor level, both at top and bottom, so that each car may operate between and serve each and every floor.

Another object is the provision of means for preventing interference between any of the cars when entering or leaving a branch terminal.

Another object of the invention is the provision of an elevator system in which a plurality of cars simultaneously operate in a common hatchway together with a hoisting unit for each car and a single driving means for all of the said hoisting units.

Other objects of the invention will appear hereinafter, the novel combinations of elements being pointed out in the appended claims.

The invention is particularly adapted to provide for the heavy traffic found in most high buildings, and for which as now arranged requires a large number of elevators, each of which must have its own separate shaft or hatchway. As the height of buildings increases the necessary additional elevators required to accommodate the increased number of tenants, necessarily increases the total space taken up by the elevators, thereby placing a practical limit upon the height to which modern buildings may be erected. By arranging and operating a plurality of elevator cars in a common hatchway a very substantial economy in rentable space is secured, both as regards that taken up by elevator shafts or hatchways and that required by the motive power devices and connections. A further economy of space and equipment is secured by means of employing a single motive power for operating a plurality of elevator cars.

The invention will be more particularly described with reference to the embodiment thereof shown in the accompanying drawings.

Figure 1 is a diagrammatic elevation view of a multiple elevator system containing an embodiment of my invention; Fig. 2 is a single motor driven multiple hoisting device; Fig. 3 is a sectional view of one of the hoisting units; Fig. 4 is a section of Fig. 2 taken on the line *a*—*a* showing the construction of a brake device; Fig. 5 is a modification of Fig. 2; Fig. 6 is a sectional view of one of the hoisting units shown in Fig. 5; Fig. 7 is a sectional view of Fig. 5 taken on the line *b*—*b*; Figs. 8 and 9 show the electrical operating and controlling circuits arranged at the upper and lower terminals, respectively, and intermediate portions of the hatchway.

Referring to Fig. 1, I show three elevator cars, A, B and C, which are operatively connected by means of the suspension cables 4, 5 and 6, to the hoisting drums or sheaves 1, 2 and 3, respectively. The main hatchway 7 may extend, as shown, from the bottom to the top of the building and is provided with branches 8 and 9 at the upper part of the building and the branches 10 and 11 at the bottom of the building. The car A travels from the branch hatchway 8 to the branch 10 while the car C travels from the branch 9 to the branch 11, the car B always travels in the main hatchway 7. Suitable guide sheaves such as 12—12 are provided properly to guide the suspension cables 4, 5 and 6, which latter are connected to the

respective cars A, B and C, at suitable points, such as 13, 14 and 15, respectively, the cables 4 and 6 being offset a trifle so that they will not interfere with each other during the normal travel of the cars up and down. Each car may be provided with guide rollers at the upper corners thereof while the cars A and C have additional rollers such as 16 and 17 upon the lower left and right hand corners, respectively, which serve the purpose of guiding the cars from the main hatchway into the respective branch hatchways. The rollers 16 and 17 engage the switches 18 and 19, respectively, as the cars A and C descend and thereby deflect them into the proper branch hatchway. No switches are provided for the upper branch terminals as the same are not considered necessary since the deflected pull of the cables 4 and 6 will be sufficient to carry the cars A and C into their corresponding upper branch hatchways. The car guides are preferably located in back of the cars as also are the suspension cables, although this particular arrangement is not necessary, but is shown that way in the present instance in order to simplify the diagram and avoid complication.

Referring to Fig. 2 which illustrates the driving machinery, it will be seen that the same comprises an electric motor 20, which is connected through a starting device 21 to the power mains *a*, *b* and *c*. The motor 20 operates a small generator 22 which supplies the current necessary for the various operating circuits hereinafter described in connection with Figs. 8 and 9. The motor 20 is geared to a shaft 23, which carries a number of gears such as 24 and 25. The gear 24 drives a gear 26 through an idler or intermediate gear 28; while the gear 25 meshes directly with a gear 27. It will be observed that the gear 24 is substantially the same size as the gear 26, while the gear 25 is the same size as the gear 27, the arrangement being such that the gears 26 and 27 will be rotated by the gears 24 and 25 at substantially the same speed, but in opposite directions. The gears 24 and 25 and the mechanism driven thereby constitute one of the hoisting units all of which are similar, and operate in the same manner. The detail construction of each hoisting unit is clearly shown in Fig. 3 in which the drum or sheave 1 is rigidly secured by a key or otherwise to the shaft 30. The gear 26 is provided with an annular recess which contains a magnet winding 31, the terminals of which are brought out to the collector rings 32 mounted upon but insulated from a boss or extension to the left hand end of the gear 26. This gear is free to turn upon the shaft 30 and is bushed with an anti-friction lining 34. The gear 26 is normally maintained out of frictional driving en-

gagement with the drum or sheave 1, by means of a spring 33, but is brought into driving engagement therewith whenever the magnet winding 31 is energized. The gear 26 being under these circumstances bodily moved against the co-acting friction face of the drum or sheave 1 and is in effect a magnetic clutch. Brushes 35 bear against the collector rings 32 at all times and serve to convey current to the magnet winding 31. The gear 27 is arranged with a magnet winding 31' and collector rings 32' similar to the gear 26, just described. An electromagnetic brake is shown at 29 and comprises a pair of brake shoes 36 carried upon brake levers 37 which are pivoted at 38 to a stationary bracket 39 (Fig. 2). The brake shoes 36 are adapted to be forced into frictional engagement with a brake surface 35 formed integral with the hoisting drum 1 by means of a compression spring 40 and to be released therefrom by means of an electromagnet 41.

The operation of the device shown in Fig. 2 is as follows: Since the shaft 23 rotates at substantially constant speed in one direction the gears 26 and 27 will rotate at a corresponding speed but in opposite directions. If now the magnet winding 31 be energized by an electric current, the gear 26 will be drawn into frictional driving engagement with the drum or sheave 1 and the latter will rotate in a direction to hoist or lower the car connected thereto, it being understood that the brake magnet 41 is energized concurrently with that of the magnet 31. As soon as the circuit of the magnet 31 and brake magnet 41 is interrupted, the spring 33 moves the gear 26 out of driving engagement with the drum or sheave 1 and the brake is applied to stop the car. Should the magnet winding 31' be energized the gear 27 will form a driving connection between the shaft 23 and drum or sheave 1 as in the case of the gear 26, only in the present instance the drum 1 will rotate in the opposite direction. From this it is seen that by energizing the windings 31 or 31' together with the brake magnet 41, the elevator car may be raised or lowered at will and at a speed depending upon the amount of energization of the windings 31 and 31', that is to say, if a weak current be sent through the winding 31 for instance, the gear 26 will drive the drum 1 at slow speed, since slipping will take place between the frictional driving faces of the gear and the drum, whereas if a stronger current be sent through the winding 31 the magnetic clutch action will be powerful enough to prevent slipping and the drum will be rotated at its maximum speed or at the same speed as the shaft 23. The other hoisting units are similarly arranged to that just described.

The apparatus illustrated in Fig. 5 is in certain respects similar to that shown in Fig. 2, only instead of using an electro-magnetic clutch between the shaft 23 and the drum or sheave 1, I propose to use a fluid clutch which may be, and preferably is, electro-magnetically controlled. Referring to Figs. 5, 6 and 7, it will be seen that each gear of each hoisting unit carries upon it a fluid clutch comprising an eccentric 42 securely keyed to the shaft 30, and an eccentric strap 42 connected to a trunk piston operating in a cylinder 48 secured to the gear 27. The eccentric strap 42 is also connected by a link 45 to the trunk piston 46 of a cylinder 47 arranged diametrically opposite the cylinder 48 and secured to the gear 27. The cylinders 47 and 48 are in communication through a pipe 49 having a valve 50 which is controlled by a link 51 connected to a ring 52 which is free to turn about a grooved sleeve 54 arranged to slide along the shaft 30. This sleeve may be moved along the shaft by means of an electro-magnet 56 (Fig. 5), which is connected by a bell crank 55 to a ring 53 carried in a groove in the sleeve 54. Both cylinders 47 and 48 contain fluid as also does the pipe 49 and in order to insure that they shall at all times be supplied with fluid, I provide a reservoir 52' containing fluid which is connected through the check valves 53', 53', to the pipe 49 on opposite sides of the valve 50. Normally the valve 50 is in open position as shown, and as the gear 27 is driven by the gear 25 on shaft 23, the pistons 46 and 44 operate in opposite directions causing the fluid to surge back and forth through the pipe 49 substantially without producing any torque in the shaft 30 and connected drum or sheave 1. If now the electro-magnet 56 be partially energized and the brake released, the valve 50 will be moved to restrict the passage of fluid from the cylinder 47 to the cylinder 48 and vice versa, and the shaft 30 and connected drum will rotate at slow speed. If the magnet 56 be fully energized, the valve 50 will be entirely closed and a positive driving connection will be established between the gear 27 and shaft 30 and the drum or sheave 1 will rotate at full speed. The gear 26 carries upon it a fluid clutch similar to that just described only operating to drive the drum 1 in the opposite direction when the magnet 57 is energized.

In order to safeguard the multiple elevator system from the possibility of collision or carelessness on the part of the operators of the several cars, I provide the system of electrical circuits clearly shown in Figs. 8 and 9. Each car, such as C, contains a controlling switch 58 which is adapted to close a circuit to the magnets 31 and 31' of Fig. 2, or the magnets 57 or 56 of Fig. 5,

through a resistance such as 60 and the resistance controlling contacts 59 and also a circuit to the brake-releasing magnet 41. A circuit breaker such as 61 is also carried upon each car, and is automatically operated from its central position as shown to stop the car by interrupting the operating and brake magnet circuits under certain conditions. Each car carries a detent such as 62, shown on the car C, which is adapted to control a switch 63 and a switch 65 which are one pair of a series of three pairs, located at the bottom and at an intermediate point in the hatchway, respectively. Safety magnets such as 66 are arranged upon certain of the floors and control a stop 67 which is moved into the path of the circuit breaker levers of each car, such as the lever 61 of car C, by means of a spring 68 and may be withdrawn out of engagement therewith by means of its magnet. Non-interference self-holding magnets 69, 70 and 71, are connected in the operating circuits of the corresponding cars and they control contacts which in turn control the proper operation of the car, as they approach or leave the lower terminals. The safety magnets 66, 72, 73, etc., are connected to a series of contact strips such as 74, located in the hatchways and these strips are arranged to be electrically engaged by a pair of contacts such as 75 and 76, carried upon each car. As before pointed out, the current necessary for the operating circuits may be generated by the dynamo 22 which runs continuously with the power motor 20.

The operation is as follows: Assuming the operator of car C desires to go up, he moves the controlling lever over the contacts 59 to close a circuit to the magnet winding 31 and brake magnet 41 in series. This circuit may be traced from the dynamo brush 82, wire 81, wire 83, magnet 71, contacts 84 of relay 70, contacts 85 of relay 69, wire 86, contact of circuit breaker 61, operating switch 58, resistance 60, wire 77, magnet winding 31, brake magnet 41, to the dynamo brush 87. The car C now starts upwardly, its speed depending upon the amount of resistance 60 included in series with the clutch magnet 31, which of course is under the direct control of the operator in the car. It will be observed that the operating circuit just pointed out includes the relay magnet 71, hence the same is energized to raise its core, thereby separating the contacts 79 and 88 and closing the contacts 89. The contacts 79 include the operating circuit of the car A, hence at this time, the latter cannot be moved away from the bottom landing. The contacts 88 control a circuit from the operating switch of car B, and the latter circuit would be opened at this time were it not that the contacts 90 of switch 91 are in closed relation, thereby forming a by-pass around

the contacts 88. The closing of the contacts 89 of relay 71 establishes a self-holding circuit for the same which circuit is in series with the lower contacts 92 of switch 65 and the contacts of switch 93 at the bottom of the branch hatchway provided for the car C. This self-holding circuit may be traced from the dynamo brush 82, conductor 81, wire 83, winding 71, wire 94, contacts of switch 93, wire 95, contacts 92 of switch 65, wire 96, self-holding contacts 89, and by wires 97 and 98 to the dynamo brush 87. Hence the magnet relay 71 will remain energized just as long as the switches 93 and 65 remain in the positions shown or until the car C has passed beyond the second floor and the detent 62 opens the contacts 92 or until the car C has reached the lower terminal and opened the switch 93. While the car C is within the limits bounded by the switches 65 and 93 the car A cannot be moved while the car B may proceed in either direction without opposition.

25 The operation of the non-interference relays 69 and 70 is similar to that just described and they co-act with the corresponding cars and switches 63 and 99, and switches 91 and 100, to prevent the movement of a car in the lower terminal while another car is being operated in the terminal, or has stopped therein. If all of the cars should be at the lower terminals, any one may be operated at will, but as soon as 30 that particular car has started away, the operating circuits of the other cars will be interrupted and maintained interrupted until the car has proceeded above the second floor landing and has moved one of the switches 100, 91 or 65 into a position to break the self-holding circuit of the relay corresponding to the active car.

In order to prevent the too near approach of one car to another when traveling in the 45 common hatchway, I provide the safety magnets 66, 72, 73, etc., which are controlled by the contacts 75 and 76 on each car, co-acting with the vertical contact strips such as 74. These safety magnets are all connected in series across the terminals of the generator 22, and their detents such as 67 will be retracted out of engagement with the circuit breakers of the several cars such as that shown at 61 in the car C in 50 opposition to the spring 68. These detents are moved into operative position by means of their springs whenever the corresponding safety magnets are deenergized. This may be done by opening their circuits or 55 by by-passing or short-circuiting the magnet windings which latter method is the preferred one and is effected by the contacts such as 75 and 76 carried on each car co-acting with the contact strips such as 74.

65 The operation of these safety magnets

is as follows:—in Fig. 9, the car C is stopped at the second floor landing with its contacts 75 and 76 bridging the contact strips 74 and 101, respectively. Now the contact strips 74 are connected across the 70 terminals of the safety magnet 73 while the contact strips 101 are connected across the terminals of the safety magnet 66, hence these two magnets are by-passed or short-circuited and are moved into engaging position by means of their respective springs as shown. It will be observed that if a car should approach too near the car C from either direction, it will be stopped by the opening of its circuit-breaker by the detents 75 67 or 102, before the cars could collide. The detent 67 will remain in operative position until the contact 76 of car C will have moved off of the contact strips 101 while the detent 102 will be retracted by the energization of the safety magnet 73 upon the contact 75 of car C leaving the contact strips 74. The remaining safety magnets act in a similar manner to that just described, the series of contact strips through 80 90 out the common hatchway being so arranged as to effect the desired result. At the upper terminals of the elevator system (Fig. 8) are arranged a number of safety magnets 103, 104 and 105, which may be simultaneously short-circuited by means of the contact strips 108, 109 and 110, and the contacts of each car, such as the contacts 111 and 112 of the car B. The contact strips 109 are shown short-circuited by the car B, 100 hence the detents of the safety magnets 103, 104 and 105, will all be in outward 95 position as shown. It will be observed that when a car is at one of the upper terminals in any of the hatchways, the contacts such as 106 of such car have moved off of the contact strips such as 110 and the magnets are all energized to withdraw their detents. Under these conditions any one of the cars 105 may leave its terminal, but almost immediately thereafter the magnets 103, 104 and 105 are deenergized to prevent the operation of any other car away from the upper terminal. After one car has left the upper 110 terminal it must proceed until the interconnected contact strips 110, 109 or 108 are open-circuited before another car can start away. This arrangement prevents interference between the cars while they are leaving the upper terminal and precludes the possibility of collision of the cars.

The electrical system of circuits shown in Figs. 8 and 9 are such that there can be no possibility of collision or interference between any of the cars during their travel 125 from one terminal to another. The safety magnets 103, 104 and 105 take care of the upper terminal, while the remaining safety magnets take care of the common hatchway, and the self-holding magnets 69, 70 and 71, 130

together with the switches 100, 91, 65, 99, 63 and 93 insure proper operation of the cars, no matter how carelessly they may be handled by their respective operators.

5. Each car may be, and preferably is, equipped with the usual mechanical safety appliance or any other feature found necessary or desirable on elevator systems in general. The saving in rental space effected 10 by my invention is of great importance, since it is possible and practical to enable three or more elevator cars to be operated in substantially the same space usually allotted to one, the only extra space required being that taken up by the branch 15 hatchways and the additional hoisting units which is taken up at the bottom and top floors where it can be well spared.

What I claim as new and desire to secure 20 by Letters Patent of the United States is:—

1. In an elevator system, the combination of a main hatchway, branch hatchways radiating therefrom at both ends, and means for independently operating a plurality of 25 suspended cars in said hatchways.

2. In an elevator system, the combination of a main hatchway, branch hatchways connected thereto, and means for independently operating a plurality of suspended 30 cars in said hatchways.

3. In an elevator system, the combination of a main hatchway, branch hatchways connected thereto, and means for operating a plurality of suspended cars in said hatch- 35 ways.

4. In an elevator system, the combination of a main hatchway, branch hatchways connecting therewith, and means for operating a plurality of cars in said hatchways.

40 5. In an elevator system, the combination of a main hatchway, a branch hatchway connected thereto, and means for operating a car in both directions in said hatchways.

6. In an elevator system, the combination 45 of a main hatchway, a branch hatchway connecting therewith, and means for operating a suspended elevator car in said main and branch hatchways.

7. In an elevator system, the combination 50 of a main hatchway, a branch hatchway leading therefrom, and means for operating an elevator car in said main and branch hatchways.

8. In an elevator system, the combination 55 of a main hatchway, a branch hatchway leading therefrom, and means for operating an elevator car in both directions in said main and branch hatchways.

9. In an elevator system, the combination 60 of a main hatchway, a branch hatchway connected thereto at an intermediate point thereon, and means for operating an elevator car in said main and branch hatchways.

10. In an elevator system, the combina- 65 tion of a main hatchway, arranged between

two terminals, branch hatchways leading from said terminals and connected with said main hatchway, and means for operating elevator cars in said main and branch hatchways.

11. In an elevator system, the combination of a main hatchway arranged between opposite terminals, branch hatchways leading from said terminals and connected with the main hatchway at intermediate points 75 therein, and means for simultaneously operating a plurality of cars in said hatchways.

12. In an elevator system, the combination of a main hatchway arranged between 80 opposite terminals, branch hatchways leading from said terminals, and connected with the main hatchway at intermediate points therein, and means for simultaneously operating a plurality of cars in both directions 85 in the said hatchways.

13. In an elevator system, the combination of a plurality of cars, a common hatchway for all of said cars, branch hatchways for some of the cars, and means for prevent- 90 ing collision of the said cars when operating in the said main and branch hatchways.

14. In an elevator system, the combination of a main hatchway and terminal therefor, a branch hatchway leading from said terminal into the main hatchway, a car adapted to move in the main hatchway, another car arranged to move in the said branch and main hatchways, and means for preventing the simultaneous operation of the said cars 100 when one of them is at a terminal.

15. In an elevator system, the combination of a main hatchway, terminals at each end thereof, branch hatchways leading from said terminals into the said main hatchway, 105 a plurality of elevator cars operating in said hatchways, and automatic means for effecting the stopping of any of the cars depending upon the position of such car with respect to any other car.

16. A multiple elevator system comprising a vertically guided cage, one or more other cages and means to guide them upon inclined paths toward and from the path of the vertically moving cage, and means 115 connected for operating the cages independently.

17. The combination in an elevator system of a plurality of converging ways, cages supported each in a vertical position 120 to travel upon the different ways, and means connected with all of the cages to reciprocate the same independently on the different ways.

18. The combination with the plurality of 125 converging ways and a cage for each way, of a plurality of drums and suspensors, a driving mechanism common to all the drums, and means independently controllable from the different cages for engag- 130

ing and disengaging the different drums and the driving mechanism.

19. In an elevator system, the combination of a plurality of hatchways radiating from a common point, and means for independently operating a suspended car in each of said hatchways.

In testimony whereof, I have signed my name to this specification in the presence of two subscribing witnesses.

WILLIAM D. BALDWIN.
